STRIPPER MECHANISM

This U.S. Pat. application is a continuation of Ser. No. 578,740, filed Sept. 12, 1966, now abandoned.

The present invention relates to mechanisms for separating mold and ingots and more particularly to stripper mechanisms having mold and ingot engaging means which move the ingot and mold relative to one another to separate the same.

It is an important object of the present invention to provide a new and improved stripping mechanism for stripping a mold from an ingot and having a frame carrying ingot engaging means and mold engaging means, the arrangement being such that the mold is stripped from the ingot by moving the ingot and mold relative to each other by the respective mold and ingot engaging means without requiring a change in the position of the frame.

Another object of the present invention is to provide a new and improved mold stripping mechanism having a frame carrying an axially fixed ram adapted to engage an ingot in a mold, tongs adapted to engage the mold, and power means operatively connected to the tongs for moving the tongs vertically relative to the ram and frame to strip the mold from the ingot.

A further object of the present invention is the provision of a new and improved stripping mechanism which is adapted to be connected to and supported by an overhead support, such as an overhead crane, and which stripping mechanism has a frame carrying an ingot engaging ram fixed thereto, mold engaging tongs supported for pivotal movement about generally horizontal axes to engage the mold and vertically movable relative to the frame by hydraulic cylinders on either side of the ram to move an engaged mold vertically relative to the frame and relative to the ram and strips the mold from the ingot.

A still further object of the present invention is the provision of a new and improved portable stripping mechanism, as noted in the next preceding object, wherein the tongs are guided and moved as a unit during vertical movement by a guide member operatively interconnecting the tongs and arranged to slide along the frame.

Another object of the present invention is to provide a new and improved stripping mechanism having a pair of mold gripping tongs supported and moved vertically by hydraulically operated piston and cylinder type motors and wherein tubular members are connected to the piston rods and surround the rods to protect them from dirt and other debris.

Another object of the present invention is the provision of a new and improved compact, portable ingot stripping mechanism comprising a frame having a vertically extending mast and a power deck extending transversely of an intermediate portion of the mast, an ingot engaging ram fixed to and depending from the lower end of the mast, a pair of mold engaging tongs disposed on opposite sides of the ram, a pair of piston and cylinder type hydraulic motors operatively connected to the mast and extending parallel to the mast, and operable to move the tongs vertically relative to the frame and ram, pump means supported on the power deck on one side of a vertical plane passing through the hydraulic motors and mast and operable to direct fluid to the hydraulic motors and an electrical motor on the power deck on the opposite side of the plane and operatively connected to the pump to provide a positive drive for the pump means.

Further objects, advantages and novel characteristics of the invention will become apparent from the following detailed description of a preferred embodiment of the invention and accompanying drawings in which:

FIG. 1 is a side elevational view of a stripping mechanism embodying the present invention;

FIG. 2 is a sectional view of the stripping mechanism taken substantially along line 2-2 of FIG. 3;

FIG. 3 is an end elevational view of the stripping mechanism of FIG. 1 as viewed in the direction indicated by arrow 3-3;

FIG. 4 is a sectional view of the stripping mechanism taken substantially along line 4-4 of FIG. 1; and

FIG. 5 is a sectional view of the stripping mechanism taken substantially along line 5-5 of FIG. 1.

The present invention provides a portable stripping unit which is readily attachable to an overhead support, such as standard overhead cranes which are in common use in steel mills or the like where ingot casting operations are performed. The stripping unit, according to the present invention, is of a compact design rendering it advantageous for storage and is quickly attachable to the hook of a standard crane. In addition, the stripping unit may be controlled from the operator's station on the crane by coupling a control cable carrying power and control lines from the crane to a corresponding cable on the unit.

The stripping unit of the present invention is particularly suitable for being supported and operated from an overhead crane and will be so described in the preferred embodiment of the invention. The stripping mechanism shown in the drawings is indicated generally as 10. The mechanism 10 comprises basically a frame A, a mold hoisting means B and an ingot engaging means or ram C. The mold hoisting means B and the ingot engaging means C are supported by the frame A and operate to strip a mold D from an ingot E without requiring the frame elevation to change once the mechanism is positioned in operative relationship with the mold D. The stripping operation is accomplished by positioning the mechanism 10 so that the ram engaging means C is directly above and engageable with the upper end of ingot E. The mold hoisting means B is operated to grip the mold D and move the mold D and ingot E vertically relative to the ram C and frame A. When the ingot E contacts the ram C, continued vertical movement of mold D strips the mold from the ingot.

The frame A comprises a vertically extending portion or mast 12 and an interconnected transversely extending portion or power deck 14. The upper end of mast 12, as viewed in the drawings, has a pair of spaced, generally triangular-shaped plates 16 and 18. The apexes of plates 16 and 18 receive the ends of a horizontally extending hook engaging bar 20. The bar 20 is engaged by the usual hook 22 of the overhead crane 40 to connect the mechanism 10 to the crane.

The lower end of mast 12 supports the ingot stripping means or ram C. The ram C is fixed at its upper end to mast 12 and has an ingot engaging surface 28 at the lower end which is arranged to abut the upper smaller end of ingot E. The upper end of ram C is received in an opening in the lower end of the mast 12 and is suitably secured to prevent it from moving axially relative to the frame. The ram C engages the top or the small end of the ingot E as the mold D is moved vertically relative to the ram by the mold hoisting mechanism B.

The mold hoisting mechanism B includes a pair of tongs 30 and 32 generally of U-shaped configuration, as viewed in FIG. 3, and are mounted for pivotal movement about generally horizontal axes by pins 34 and 36, respectively. The opposite ends of pin 34 are received in bearings 37 and 38 formed integral with the legs of the U-shaped tong 30. The ends of pin 36 are received in bearings 40 and 41 formed integral with the upper ends of the legs of tong 32. This mounting arrangement permits the tongs 30 and 32 to pivot and move the lower ends of the tongs toward and away from one another, as represented by the full and broken line showings of the tongs in FIG. 1. The tongs are moved towards each other to grip a mold. The mold D has a pair of lugs 42 at the upper end and the tongs 30 and 32 have lug engaging lips or portions 44 and 46, respectively, at their lower ends. The lugs 42 and lips 44 and 46 have complementary mating surface configurations in the form of an ogee curve, as shown in FIG. 2, and which cooperate when engaged to connect the mold D to the tongs 30, 32. The tongs are disconnected from the mold by moving away from one another, as shown by the broken line representation of the tongs in FIG. 1.

The tongs 30 and 32 are moved towards and away from one another by a hydraulic motor 50. The motor 50 has a cylinder 52 within which a piston and piston rod 54 reciprocate upon 75 the application of fluid to either side of the piston. The

cylinder 52 is pivotally connected to tong 32 by a pin 56. The pin 56 extends through two spaced connector members formed integral with bearing 40 of tong 32 and through a connector member fixed to the end of cylinder 52 and positioned between the spaced connector members. The piston rod 54 is pivotally connected to tong 30 by a pin 58. The pin 58 extends through the end of the piston rod 54 and through aligned connector members formed integral with bearing 38. As fluid under pressure is introduced into the right-hand end of cylinder 52, as viewed in FIG. 1, the cylinder 52 and piston and piston rod 54 move in opposite directions away from one another and pivot the lower ends of tongs 30 and 32 toward one another. When fluid is introduced into the left-hand end of cylinder 52, the cylinder 52 and piston rod 54 move in opposite directions toward one another pivoting the lower ends of tongs 30 and 32 away from one another.

The tongs 30 and 32 are supported by frame A for vertical movement by a pair of fluid motors 60 and 62. Motors 60 and 62 include cylinders 64 and 66 pivotally connected at their upper ends to plates 16 and 18. The cylinders 64 and 66 extend through openings 67, 68, respectively, provided in power deck 14. Pistons 69 and 70 reciprocate in cylinders 64 and 66, respectively, in response to fluid pressure acting on opposite sides thereof. The piston rods 72 and 74 are fixed at their upper ends to the pistons 69 and 70, respectively, and receive the pins 34 and 36, respectively, through their lower ends. The motors 60, 62 support the tongs 30, 32, respectively, and move the tongs vertically relative to frame A.

The tongs 30, 32 are maintained in spaced relationship by a guide member 84. The guide member 84 interconnects the tongs 30, 32, pins 34, 36, and motors 60, 62 so that these parts move vertically as a unit relative to the frame A. The guide member 84 is generally L-shaped in configuration with the vertically extending leg 84a being tubular and preferably rectangular in cross section. Two sides of leg 84a have horizontally extending portions at their lower ends in the form of spaced plates 85 which define the horizontally extending leg 84b of L-shaped member 84. The plates 85 have spaced openings through which the pins 34 and 36 extend. The plates 85 are assembled on the pin 34 intermediate the end of the piston rod 72 and bearings 37, 38. The plates 85 are assembled on the pin 36 intermediate the end of the piston rod 74 and bearings 40, 41. The plates 85 thus interconnect the tongs 30, 32, pins 34, 36 and piston rods 72, 74 so that these parts move vertically as a unit when the motors 60, 62 are operated.

The guide member 84 is slidably connected to the mast 12 and slides along the side 12a of the mast 12 during vertical movement thereof. The vertical leg 84a of the member 84 has a pair of flanges 86 adjacent the upper end which slide in slots 88 in the mast 12 and maintain the member 84 in proper position relative to the motor 60 during vertical movement of the tongs. Also, the sliding connection prevents the guide member 84 from moving away from the mast side 12a and insures that one of the tongs will not lead or lag the other during vertical movement.

The sides of leg 84a other than the sides formed by the plates 85 converge at their lower ends and extend about the lower end of piston rod 72 between plates 85 so that the leg 84a surrounds piston rod 72. The tubular guide member 84 telescopes about cylinder 64 of motor 60 and provides a movable dirt shield for the piston rod 72 and cylinder 64 preventing dirt and other foreign debris from entering the cylinder.

A tubular sleeve 90 is provided to shield the motor 62 from dirt, etc. The sleeve 90 is preferably circular in cross section, is connected at its lower end to pin 36 and moves therewith during raising and lowering of the tongs 30 and 32. Alternatively, the sleeve 90 may be rectangular in cross section and could be guided along mast 12 in the same manner as guide member 84.

As fluid under pressure is directed into the lower end of cylinders 64 and 66, the pistons 69 and 70 and piston rods 72 and 74, pins 34 and 36, tongs 30 and 32, guide member 84 and

sleeve 90 are moved vertically upwardly along mast 12 as a unit relative to frame A. The open upper ends of leg 84a and sleeve 90 permit them to telescope about the cylinders 64 and 66. The leg 84a and sleeve 90 are of sufficient length to shield the piston rods 72, 74 from dirt and other debris at all extents of projection from their cylinders. When fluid is exhausted from the lower end of the cylinders 64 and 66, the piston rods 72, 74, tongs 30, 32, and member 84 and sleeve 90 move downwardly along mast 12. Provision is made for directing fluid into the upper end of cylinders 64 and 66 in the event this is necessary or desired.

Fluid under pressure for operating servomotors 50, 60, and 62 is provided in part in the preferred embodiment by an electric motor 92 supported on the power support deck 14. The motor 92 drives pump means 94 also located on the power deck 14 the other side of mast 12. A positive drive is provided from motor 92 to pump means 94 by a shaft 96 which drives the pump means 94 through suitable gears, not shown. The open sides of mast 12 allow for passage of shaft 96 therethrough enabling a positive drive to be used for the pump means 94. Suitable controls, including solenoid operated valves, are provided to control the application of fluid from a fluid reservoir on the platform 14 through the pumps to the servomotors 50, 60 and 62. The controls are of conventional construction and are preferably operated remotely from the operator's cab of the overhead crane. The electrical power line for motor 92 and control lines are embodied in a cable running from the crane and which is connected to a similar cable on the stripper unit 10 by a suitable quick disconnect coupling.

From the foregoing, it should be apparent that a compact, relatively simple, and highly reliable portable ingot stripping mechanism has been provided by the present invention. The stripper unit 10 is quickly connected to the hook 22 of an overhead crane and the operation can be controlled from the crane by coupling the cable which carries power and controls lines to the unit. Once connected, the crane can move the stripper unit 10 into an operative relationship with the mold D. When the unit 10 is properly positioned in relationship to the mold D with the tongs 30 and 32 open, motor 50 is operated to cause the lower ends of tongs 30 and 32 to move toward one another until the lips 44 and 46 on the lower end thereof engage the lugs 42 on the mold D which connects the mold to the tongs. Fluid is directed into the lower end of cylinders 64 and 66 by operation of the valves which move the tongs 30 and 32, mold D, and ingot E vertically relative to the frame A and relative to the ram C. As the ingot E engages the stationary ingot engaging end 28 of the ram C, relative movement is effected between the ingot E and mold D due to the continued hoisting of the mold D by the motors 60 and 62. This relative movement strips the mold D from the ingot E without requiring the frame A to be moved by the crane. After the stripping operation has been accomplished, the mold D can be moved to any desired location by operation of the overhead crane. The mold is released from the stripper unit by operating motor 50 to move tongs 30 and 32 out of engagement with the lugs 42. The stripper unit 10 is then ready for another stripping operation.

Although the preferred embodiment of the present invention has been described in considerable detail, it is intended to cover all modifications, adaptations, and changes which come within the scope of the appended claims.

I claim:

1. In a stripping mechanism, a frame, a pair of cylinders supported by said frame, each of said cylinders having a piston reciprocable therein and a piston rod fixed to said piston and extending from said cylinder, a pair of mold engaging tongs connected to said piston rods and a pair of tubular members, each of said tubular members having an open end and being connected at its opposite end to one of said piston rods, said tubular members surrounding the associated piston rod and arranged to telescope about the associated cylinder as the piston rods are moved relative to the cylinders to thereby provide a movable dirt shield.

2. In a portable mechanism for stripping a mold from an ingot, a frame, a central support fixed to the frame adjacent to the top thereof adapted to detachably receive a lifting device to suspend said mechanism from an overhead support, an abutment or ram fixed to said frame in a position to engage an end of an ingot contained in a mold, mold engaging tongs adapted to grip the mold, means supporting said tongs on said frame for vertical movement relative to said frame, and means to move said tongs vertically relative to said frame, whereby the mold is stripped from the ingot without requiring a change in the position of said frame and ram.

3. A stripping mechanism as defined in claim 2 including a guide surface on said frame and a guide member connected to said tongs and slidable along said guide surface.

4. In a portable ingot stripping mechanism, a frame, means fixed on said frame for detachable connection of said frame to an overhead lifting device, an ingot-engaging ram integral with said frame and projecting vertically downward therefrom, a pair of mold-engaging tongs, means supporting said tongs for pivotal movement about horizontal axes and for vertical movement relative to said frame, first power means operatively connected to said tongs to effect pivotal movement of said tongs about said horizontal axes, and second power means operatively connected to said tongs to effect vertical movement of said tongs relative to said frame.

5. In a portable ingot stripping mechanism, a frame having a power support deck extending transversely of an intermediate portion thereof, means fixed on said frame adapted for detachable connection to an overhead lifting device, an ingot engaging ram fixed to and depending from the lower end of said frame, a pair of piston and cylinder type hydraulic motors supported by said frame and extending parallel with said ram, a pair of mold engaging tongs connected to and carried by said hydraulic motors and being movable relative to said frame in a direction parallel to the length of said ram by said motors, pump means on said support deck to one side of a plane passing through the longitudinal centerline of the hydraulic motors and operable to direct fluid to the hydraulic motors,

motor means on the said deck on the opposite side of said plane from said pump means, and means coupling said motor means to said pump means to drive said pump means.

6. In an ingot stripping mechanism, a frame, a ram fixed to and depending from said frame, a pair of side-by-side piston and cylinder type hydraulic motors supported by said frame, each of said motors being extendable parallel with the length of and alongside said ram, a pair of tongs adapted to engage a mold, one tong of the pair being connected to and supported by one of said motors and the other tong being connected to and supported by the other motor, both said tongs being movable by said motors in the direction parallel with the length of said ram, and means interconnecting said tongs and guiding them as a unit for movement in the direction parallel with the length of said ram.

7. In an ingot-stripping mechanism, a frame, a pair of cylinders supported by said frame, each of said cylinders having a piston reciprocable therein and a piston rod fixed to said piston and extending from said cylinder, a pair of tongs connected to said piston rods and adapted to engage a mold, and a guide member interconnecting said piston rods and having a guide portion slidably connected to said frame to provide for movement of said tongs vertically as a unit, said guide member comprising a vertically extending portion of tubular configuration and a horizontally extending portion at the lower end of the vertically extending portion, said vertically extending portion of said guide member surrounding one of said piston rods and having flange means slidable in guideways provided in said frame whereby said vertically extending tubular portion telescopes about the cylinder of said one piston as the guide member moves vertically along said frame.

8. A stripping mechanism as defined in claim 7, wherein said guide member includes a horizontally extending portion comprising a pair of spaced plates at the lower end of said vertically extending portion, a pair of pins interconnecting said piston rods, said tongs and said guide member, each of said pins extending through aligned openings in one of said tongs, said plates and one of said piston rods.
